UNITED STATES PATENT OFFICE.

WILLIAM H. FRATER, OF DETROIT, MICHIGAN, ASSIGNOR TO AMERICAN AUTOPARTS COMPANY, OF DETROIT, MICHIGAN, A CORPORATION.

APPARATUS FOR FORMING SPRING PLATES.

Application filed July 18, 1923. Serial No. 652,263.

This invention relates to a new and improved adjustable form for shaping material and more specifically to an apparatus particularly adapted for forming curved 5 springs or similar articles.

Articles such as springs are formed by being pressed to the desired shape while heated to a proper temperature and are then quenched while maintained in the desired 10 shape. When so treated and properly quenched they maintain the desired contour upon being released from the form. Springs of this character are used formed to a wide 15 variety of contours. It is consequently customary to provide adjustable shaping means which may be adapted to form the various shapes desired.

It is obviously necessary for practical and 20 efficient operation of such shapers that the forms engaging the material are such as to permit adequate contact of the spring being formed with the quenching fluid. Where, as 25 is customary, the springs are formed upon circular arcs, the changing of the adjustment 30 of the forming elements from one arc to another is a lengthy operation requiring great care since each form element must be adjusted an amount differing from the adjacent elements.

It is an object of the present invention to 35 provide a new and improved apparatus for forming curved articles comprising a form consisting of a plurality of relatively adjustable elements together with means for simultaneously adjusting the elements.

It is a further object to provide an apparatus of this character in which the elements 40 throughout their range of adjustment may be maintained in predetermined geometric relation.

It is an additional object to provide an 45 apparatus of this character consisting of movable cams adapted for simultaneous operation, the cams engaging the various elements differing in contour whereby the elements may be simultaneously differentially adjusted.

It is an additional object to provide means 50 of this character in which the forming elements are yieldingly maintained in engagement with the adjusting means.

Other and further objects will appear as the description proceeds.

I have illustrated a preferred embodiment 55 of my invention in the accompanying drawings, in which—

Figure 1 is a plan view of an apparatus embodying the present invention;

Fig. 2 is a section taken on line 2—2 of Fig. 1; and

Fig. 3 is a side elevation of the apparatus, certain parts being broken away for the sake of clearness.

The apparatus comprises the tank 11 which is adapted to contain the oil quenching 65 bath, this tank being provided with the bearings 12 into which are fitted the trunnions 13 of the main frame 14. This frame is provided with suitable counterbalances and latches for maintaining it in its vertical and 70 horizontal positions. These elements form no part of the present invention and have not been shown and need not be described in detail. This main frame 14 carries the sliding frame 15 which is fitted in the guide-ways 75 16. This frame 15 is maintained at one limit of its movement, as shown in Fig. 1, by springs 17. The frame 15 has adjustably secured thereto by bolts 18, the spring members 19 which support the flexible spring- 80 forming member 20.

The frame 15 is slid longitudinally of the main frame 14 against the resistance of the 85 springs 17 by means of the arms 21 pivoted to frame 16 at 22 and having the rollers 23 engaging the edge 24 of the frame. At the inner limit of its movement the rollers 23 fit in depressions 25 and the frame is maintained in this position against the resistance of the springs 17.

The main frame 14 has the cross member 26 upon which are supported a plurality of forming elements 27. These elements are held down by the removable plate 28. The forming elements as shown in Figures 2 and 3 carry the pins 29 which are adapted to contact with the material to be formed. These pins are secured in place by bolts 30 and to the upper ends of these bolts are secured the 95 springs 31, the opposite ends of which are secured to studs 32 carried by plate 28.

As best shown in Figure 2, each element 27

carries an adjustable contact stud 33 which is threaded in an opening 34 in the element and is locked in adjusted position by nut 35.

The casting 36 is secured to the main frame 14 and provides a plurality of guide-ways for the movable cam blocks. The blocks 38 and 39 ride in guide-way 37 and are retained in the guide-way by the plate 40, held in place by bolts 41. Similarly the 10 guide-way 42 carries blocks 43 and 44, the guide-way 45 carries blocks 46 and 47, the guide-way 48 carries blocks 49 and 50 and the guide-way 51 carries the single block 52. The opposite side of the apparatus is similarly provided with blocks and guide-ways. 15

As clearly shown in Figure 3 the upper surfaces of the blocks differ as well as the slopes of the several guide-ways. Consequently the forming member associated with each block is adjusted differently from the other forming members. 20

As shown in Figure 2, which shows block 38' and its associated parts, the block is provided on its lower surface with a rack 53 which coacts with gear 54 keyed to shaft 55. This showing is typical and each block is provided with a similar rack meshing with a similar gear carried by shaft 55. It will be understood that all of the guide-ways, although differing in angle, are located on planes tangential to these gears. The shaft 30 55 is provided with a gear 56 meshing with pinion 57, the latter being rotatable by means of the squared shaft end 58. By rotating this 35 pinion the shaft is rotated and the blocks are slid in their guide-ways and the forming elements are adjusted.

In the operation of the apparatus, the blank to be formed is first heated to the 40 proper temperature and then is placed against the pins 29. The levers 22 are swung to force the member 20 against the blank and this member being flexible causes the blank to conform to the arcuate contour defined by the closely spaced pins. The entire frame 14 and its associated parts are now swung from the horizontal position in which they are shown in Figure 1 to the vertical position. This serves to carry the heated and 45 curved blank below the level of a quenching bath of oil in the tank 11. When the blank is adequately quenched, the frame and associated parts are returned to the horizontal and the blank which now maintains its curvature is removed from the pins of the contact elements by releasing the sliding frame 50 15 which is drawn to the position of Figure 1 by springs 17.

The cam surfaces upon the sliding cam 60 blocks are so related to their angle of movement that in whatever position the shaft 55 may be turned, all of the elements will maintain their contact pins upon the arc of a circle. The radius of this circle obviously 65 varies as the shaft is turned. When turned

to one limit of movement, the radius of the circle will reach infinity and the pins will be upon a straight line. The opposite limit of adjustment may be such as to bring the pins to an arc of relatively small radius, such, for example, as twenty-four inches. 70

Each of the forming elements may be adjusted individually relative to its associated cam by loosening the corresponding lock nut 35 and turning the contact stud 33. Proper 75 adjustment may be determined by rotating the shaft to bring the elements to their limit of movement at which they should be upon a straight line. The elements may then be tested by a straight edge and the proper studs 80 varied to bring them all into contact with the straight edge.

This apparatus is capable of rapid adjustment to an infinite variety of circular arcs. While throughout the present discussion reference has only been made to circular arcs, 85 it will be apparent that the cam surfaces may be so formed as to simultaneously adjust the various forming elements as to provide any desired relationship between the elements through their range of adjustment. 90

I have illustrated one preferred embodiment of my invention but I contemplate such changes and modifications as come within the scope of the appended claims. 95

I claim:

1. Apparatus for forming curved articles comprising a form consisting of a plurality of relatively adjustable elements, cams for adjusting said elements and a plurality of guide means for the cams, the guide means differing in angle and the cam surfaces differing in form, whereby the form elements are maintained upon circular arc formation throughout their range of adjustment. 100

2. Apparatus for forming curved articles comprising a form consisting of a plurality of relatively adjustable elements, cams for adjusting said elements, racks formed on said cams, and gears meshing with said racks 110 whereby the cams may be moved to adjust the form elements.

3. Apparatus for forming curved articles comprising a form consisting of a plurality of relatively adjustable elements, cams for adjusting said elements, racks formed on said cams, gears meshing with said racks, and a common shaft for said gears whereby the cams may be simultaneously adjusted. 115

4. Apparatus for forming curved articles comprising a form consisting of a plurality of relatively adjustable elements, cams for adjusting said elements, racks formed on said cams, gears meshing with said racks, a common shaft for said gears whereby the cams 120 may be simultaneously adjusted, and guide means for said cams, the guide means and cam surfaces being so related that the form elements are maintained in predetermined 125 geometric relation. 130

5. Apparatus for forming curved articles comprising a form consisting of a plurality of relatively adjustable elements, cams for adjusting said elements, racks formed on said 5 cams, gears meshing with said racks, a common shaft for said gears whereby the cams may be simultaneously adjusted, and a plurality of guide means for the cams, the guide

means differing in angle and the cam surfaces differing in form whereby the form elements are maintained in circular arc formation throughout their range of adjustment. 10

Signed at Detroit, Michigan, this 13th day of July, 1923.

WILLIAM H. FRATER.
